BEAM ACTION STRINGER

Arthur C. Horner, San Francisco, Calif.

Application March 4, 1935, Serial No. 9,331

5 Claims. (Cl. 20—1.05)

This invention relates to structural stringers and particularly to timber or wooden stringers, and it aims to provide a method and means whereby a line of stringers or simple beams are supported and connected for continuous beam action, or, considered in another light, so that the effect of a load imposed upon that portion of the stringer between any two supports will not be confined or concentrated on that portion, but will extend and be distributed beyond the supports.

Another object is to attain the results stated by splicing the ends of the simple beams in laterally overlapping relationship and in combination with supports, in a manner insuring such a strength to the resulting splices that the splice will be as strong in bending as the remainder of the individual beams.

From a practical standpoint a continuous beam conforming to the invention will be deflected considerably less than simple beams, at any loaded point and, presuming the splice to be strong enough to resist bending moment, the continuous beam action permits the use of smaller timbers than if the stringer were a series of simple beams, effecting a material saving in material.

A further aim is to provide a construction wherein driven metallic connectors or cementitious or equivalent matter, either alone or in combination may be effectively used to provide a strong splice in accordance with the invention.

Various additional objects and advantages will become apparent from a consideration of the description following taken in connection with the accompanying drawings illustrating exemplary embodiments thereof, wherein:—

Figure 1 is a fragmentary plan view of a bridge structure illustrating one form of the improved continuous beam stringer;

Figure 2 is a substantially horizontal sectional view of the structure of Figure 1;

Figure 3 is a transverse sectional view taken substantially on the plane of line 3—3 of Figure 2;

Figure 4 is a detail in side elevation of one form of metallic dowel or connector used;

Figure 5 is an end view of said dowel or connector;

Figure 6 is a detail side elevation of a modified form of the metallic dowel or connector;

Figures 7 and 8 are diagrammatic views, the former suggesting simple beam action as in the usual type of stringer and the latter contrasting therewith, the continuous beam action of the stringer produced in accordance with the present invention;

Figure 9 is a fragmentary plan view of a bridge

using a second form of continuous beam action stringers;

Figure 10 is a longitudinal sectional view taken through the bridge of Figure 9;

Figure 11 is a cross sectional view taken substantially on the plane of line 11—11 of Figure 9;

Figure 12 is a fragmentary plan view of a bridge utilizing a third form of continuous beam action stringer;

Figure 13 is a longitudinal sectional view taken through the bridge of Figure 12;

Figure 14 is a transverse sectional view taken substantially on the line 14—14 of Figure 12;

Figure 15 is a fragmentary plan view of a bridge using a further form of continuous beam stringer, 15 and

Figure 16 is a longitudinal sectional view taken on the line 16—16 of Figure 15.

The continuous beam stringer of the present invention is advantageously used in bridge building, and it has been specifically disclosed in that connection by way of example, no limitation however being implied to such use.

Referring specifically to the form of Figures 1 to 3, 10 designates piles or columns surmounted by caps or cap beams 11, usually but not necessarily of wood, which support stringer or beam members 12.

Each stringer 12 at opposite end portions rests on and is secured to one of the said caps 11. Such beams 12 are slightly angularly disposed, and such end portions overlap end portions of the adjacent stringers, the overlapping, and in this instance, contacting end portions being designated 13.

Adjacent the terminal or free ends of each stringer 12 they have 30 metallic dowels or connectors 14 driven into the sides thereof, the connectors 14 joining together the adjacent portions 13 as shown. Specifically, such connectors 14 are metallic rings or

thimbles provided with spurs or points 15 on the 40 opposite edges thereof, the connector being longitudinally corrugated, if desired, as shown in Figure 5. Obviously any form of connector

may be substituted for that specifically disclosed at 14. If desired, bolts or the equivalent 45 16 may be passed through the portions 13, which

it will be noted are surrounded by the said connectors 14. A typical loading or overdeck structure is shown as applied to the stringers 12 as at

17, consisting, for instance, of ties 18 which 50 support railway rails 19.

As a result in the construction described, a continuous beam action is assured throughout the line or lines of stringers 12, inasmuch as the

portions 13 are supported and the portions 13 55

are connected together at a plurality of points and on opposite sides of the supports. Because of the connectors 14 and bolts 16, or other fastening means, the splice produced by the portions 13 and fastenings is at least as strong in bending as the individual stringers or beams 12-12. Accordingly the action of the continuous beam under a load imposed between any two supports 11 will be that suggested in Figure 8, and which is to be contrasted from the usual single beam action suggested by the diagram of Figure 7. In said Figures 7 and 8 the supports are designated *s*. The simple beams in Figure 7 are shown at *t* while the continuous beam produced by a series of stringers 12, is designated *u* in Figure 8. It will be seen that instead of a load *P* having effect between two supports only, as in Figure 7, that such effect as in Figure 8 extends to and is distributed beyond any two supports so as to attain the continuous beam action. It has been found too that the deflection of the continuous beam as in Figure 8, will not be more than one-half of the deflection of a simple beam as suggested in Figure 7.

It is clear that the invention may be produced in various ways and forms, and that no limitation is to be implied with respect to the ones just specifically described. For instance, I may use the forms disclosed in Figures 9 to 11, employing the connector of Figure 6, rather than that of Figures 4 and 5. In such form, the piles or columns are designated 10' and the caps 11', supporting wooden stringers 12' at overlapping end portions 13'. Instead of the stringers 12' being angularly disposed like those at 12, they are straight and alternately arranged, and the portions 13' are in spaced relation with bodies 20 bonding them together. These bodies 20 are rigid, being cast to the stringers while in a plastic state, and consisting of concrete or other cementitious matter, usually using Portland cement as the bonding material. Prior to the application of the material 20, conductors or anchors 21, are driven so that teeth 22 thereof will fasten them in the sides of the portions 13'. These connectors 21 are preferably of corrugated metal and of ring shape and smooth at their opposite end, thus conforming to the form of Figures 4 and 5, except that the teeth are omitted at one end. The untoothed portion of the connector 21 projects beyond the sides of the stringer portions 13' and are anchored and embedded in the concrete or bodies 20. Such bodies, if desired, may be reinforced as suggested at 23.

Transversely of the stringers 12' an overdecking, as of timber, may be laid at 24. Braces 25 of wood or cement may be provided between the stringers, for instance, midway of their ends. It will be realized that the continuous beam action suggested by the diagram of Figure 8, will also take place under a load imposed between any two caps or supports 11' inasmuch as the bonding and connection of the stringers by the bodies 20 render the splice thus produced as strong as any part of the remainder of the stringers, giving the same coaction as the caps 11 and connections 14 in the preceding form of the invention.

In Figures 12, 13 and 14 another form of the invention is disclosed which conforms in many respects closely to that of Figures 9 to 11. The stringers 12'' in this instance are of wood and are connected and supported identically as in Figures 9 to 11, except that braces 25' corre-

sponding to those at 25 are of concrete, and such braces as well as bodies 20' corresponding to those at 20 are widened at the top as at 27 and 28. The stringers 12'' have metallic anchors 29 driven into the same, and a concrete or equivalent overdecking 30 is poured over the stringers and bodies 20' and 25', being effectively held in place by the anchor members 29 when the concrete sets or hardens. Such overdecking 30 may have metallic reinforcement as at 31, if desired. In some instances, with the aid of the appropriate forms, the bodies 20', reinforcements or braces 25' and the overdecking 30 may be poured simultaneously and constitute a single unit or integral body when set or hardened.

In the said forms of Figures 12 to 14, it will be realized that the continuous beam action is attained as in the previous forms.

Figures 15 and 16 illustrate a form identical with that of Figures 12 to 14, except that the anchors 29 are omitted and in lieu thereof, ring anchors 32 are employed, for which purpose I use connectors 21 as shown in Figure 6. These anchors or connectors 32 have their teeth 21 driven into the wooden beams here designated 12''' at any desired locations or intervals to untoothed portions of such anchors 32 projecting above the beams 12''' and being embedded and anchored in the concrete or equivalent overdecking 30', as best shown in Figure 16. Obviously in this form of the invention, the continuous beam action is attained as in all of the previous forms.

Attention is called to the fact that a material advantage of the present invention is that the continuous beam action which is attained, permits the use of smaller timbers as at 12, 12', 12'' and 12''' than is the case where the stringer is merely a series of simple beams as in Figure 7. Another point of considerable importance, especially when a concrete floor slab is used as in Figures 12 to 15, the deflection at any loaded point is less than at a correspondingly loaded point in a line of simple beams, experiments having shown that the deflection may be limited to as much as one-half of the deflection of a simple beam.

It is to be also understood that the concrete or equivalent bodies 20 and 20' are not only secured in place by the connectors or anchors 21 but that such concrete is intimately bonded and adhered to the portions of the wooden stringers with which they contact.

Various changes may be resorted to provided they fall within the spirit and scope of the invention.

I claim as my invention:

1. A continuous beam action structure comprising a line of stringers having end portions in overlapping relation, a cementitious body interposed between said end portions and bonded thereto and effective adjacent the ends of the stringers, and a connector secured to each stringer adjacent its end and anchored in said body.

2. A continuous beam action structure comprising a line of stringers having end portions in overlapping relation, a cementitious body interposed between said end portions and bonded thereto and effective adjacent the ends of the stringers, a connector secured to each stringer adjacent its end and anchored in said body, supporting means for said body and end portions, and overdecking on said stringers.

3. A continuous beam action structure comprising a line of stringers having end portions in

overlapping relation, a cementitious body interposed between said end portions and bonded thereto and effective adjacent the ends of the stringers, and a cementitious overdeck integral 5 with said body.

4. A continuous beam action structure comprising in combination with first and second supports and with an intermediate support, stringers supported on the intermediate support and the 10 first support and extending beyond each of them and terminating short of the second mentioned support, stringers disposed on the intermediate support and second mentioned support extending beyond both of them and terminating short of the 15 first mentioned support, means connecting said stringers together on opposite sides of and adjacent the intermediate support, and connecting means for the respective stringers adjacent the first and second supports at the sides thereof 20 facing the intermediate support.

5. A continuous beam action structure comprising in combination with first and second supports and with an intermediate support, stringers supported on the intermediate support and the first support and extending beyond each of them 5 and terminating short of the second mentioned support, stringers disposed on the intermediate support and second mentioned support extending beyond both of them and terminating short of the first mentioned support, means connecting 10 said stringers together on opposite sides of and adjacent the intermediate support, and connecting means for the respective stringers adjacent the first and second supports at the sides thereof 15 facing the intermediate support, the stringers being disposed in horizontal rows and each stringer contacting with the adjacent supports.

ARTHUR C. HORNER. 20
